UNITED STATES PATENT OFFICE.

JOSIAH PERCIVAL STEVENS, OF ATLANTA, GEORGIA.

INDICATOR FOR USE IN CARD GAMES.

Application filed April 23, 1923. Serial No. 634,198.

To all whom it may concern:

Be it known that I, JOSIAH P. STEVENS, a citizen of the United States, residing at Atlanta, in the county of Fulton and State 5 of Georgia, have invented certain new and useful Improvements in Indicators for Use in Card Games; and I do hereby declare the following to be a full, clear, and exact description of the invention, such as will enable others skilled in the art to which it 10 pertains to make and use the same.

The present invention relates to improvements in indicators for use particularly in connection with card games and 15 card parties to designate the dealer as much dissension arises from the failure to remember who dealt the cards last and it is for the purpose of avoiding the contentions arising from this failure and to settle finally as 20 to who the next dealer shall be that the present invention is proposed.

The invention consists in providing a compact and attractive construction designed to 25 be operated by the pencil used by the party keeping the score of the game, it being another object of the invention to make a desirable disposition of the pencil during the time each hand is being played as pencils, particularly round pencils cause much annoyance because of their tendency to roll off 30 the card table and they are generally placed against the edge of the pad on which the score is kept but this is unsatisfactory.

Other objects of the invention are to provide 35 a device simple in construction and operation for pointing to the next dealer and for providing a socket in which to receive the pencil, the act of moving the pencil into the socket causing the operation of the index 40 or pointer.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of the indicator constructed according to the present invention.

Figure 2 is a vertical section therethrough

with the parts shown in an initial position.

Figure 3 is a similar view showing a pencil as received in the socket and the parts in 55 a subsequent position.

Figure 4 is a top plan view with the cover removed and the parts in the position shown in Figure 2, and

Figure 5 is a similar view with the parts 60 in the position shown in Figure 3.

Referring more particularly to the drawings, 1 designates a base plate which is adapted to rest upon the table or other supporting surface and having a pair of rear 65 lugs 2 and 3 bent upward therefrom and having pins 4 and 5 projecting rearwardly to take into the perforations 6 in the rear wall of a cup shaped cover 7 which is placed is inverted position upon the base with its 70 rear wall extending outward of the lugs 2 and 3 and the front wall lying outward of a lug 8 also struck up from the base and being threaded to receive a locking screw 9 which passes through the front wall of the cover 7. 75 Suitable numbers are provided upon the upper face of the cover 7 as shown in Figure 1 to designate the various hands in the card game and as an example I have illustrated four such numbers for use in connection 80 with a four-handed game in which the numbers are placed at angular distances of 90 degrees or in other words the cover is marked off into quadrants and over the upper face thereof is adapted to move the pointer or index 10 mounted upon a vertically disposed 85 shaft 11 journalled in appropriate bearings in the base plate and in a supporting bracket 12 erected thereon and secured as by the fastenings 13 shown in Figures 4 and 5. This 90 bracket serves to hold the mechanism by which the pointer or index 10 is moved an angular distance of 90 degrees upon the completion of each hand of the game and by the introduction of a pencil represented in dotted lines at 14 into a socket 15 carried at the rear central portion of the base plate 1.

In the socket is a longitudinal vertical slot 16 adjacent a similar slot 17 in the rear wall of the casing, the slots permitting the rear 100 arm 18 of the bell crank lever or inclined plane to project into the socket. The bell crank lever is fulcrumed as indicated at 19 to a part of the bracket 12 and the arm 18

projects downwardly and diagonally therefrom so as to assume an inclined position within the socket 15. The forward arm 20 of the bell crank lever projects vertically downward and is pivoted to a pawl 21 that extends forward beneath a ratchet disc 22 made fast to the pointer shaft 11.

The disc 22 is provided with downwardly extending teeth 23 to cooperate with the outer end of the pawl 21, which has an inclined upper face 24 to cause the pawl to be deflected downwardly in moving back to the initial position after each actuation. The flat spring 25 bearing and sliding upon the base plate 1 is coupled to the pawl 21 and acts to yieldably urge the pawl upwardly against the bottom face of the ratchet disc.

A leaf spring 26 is secured at one end of the stop 27 upon the base plate and has its other end engaged with the pawl or the bell crank lever and acts to normally urge the parts to an initial position.

The disc 22 as shown in Figures 4 and 5 is provided with notches 28 to receive the spring tooth 29 carried by the bracket 12 for the purpose of yieldably restraining the disc against rotation until positively actuated by the pawl and for further avoiding any casual or accidental movement of the disc during the receding movement of the pawl.

In the use of the device the indicator is placed beside the pad on which the score is kept and the pencil used to mark down the score is inserted after each deal in the holder 35 or socket 15 and it is removed after each hand is played in order to set the score down. In other words the pencil reposes in the socket indicated in Figure 3 during the playing of each hand and it must be removed after the playing of each hand to set down the score so that the pointer or index 10 is moved through a quarter of a circle after each deal and consequently this pointer moves around the numbered cover 45 portion and points to the next dealer upon re-insertion of the pencil.

The pencil in entering the socket strikes the arm 18 a glancing blow and causes the bell crank lever or inclined plane to press forward pushing the pawl against a tooth 23 of the disc and forcing the disc through an angular distance of 90 degrees carrying the shaft 11 and index 10 therewith. When the pencil is removed the spring 26 pushes back the bell crank lever or inclined plane and also the pawl to the position shown in Figures 2 and 4 and the pawl 21 will ride downwardly on encountering the next subsequent tooth 23, which movement will be permitted by the spring 25.

It will thus be found that the device will reliably indicate the next dealer and will provide a suitable receptacle for the pencil while each hand is being played.

The casing or cover is of course not neces-

sary and this may be dispensed with if desired but it protects the mechanism and avoids the accumulation of dust and other foreign matter upon the moving parts of the device.

It is obvious that various changes and modifications may be made in the details of construction and design of the above specifically described embodiment of this invention without departing from the spirit thereof, such changes and modifications being restricted only by the scope of the following claims.

What is claimed is:—

1. A device for indicating dealers at cards and the like comprising a base, a socket for receiving a pencil at the back of the base, and standing substantially vertically, an inverted cup-shaped casing fitted removably over the base and lying adjacent the socket, said socket and base having registering slots, a bell-crank lever pivoted within said casing to swing in a substantially vertical plane and composed of front and rear rigid arms diverging downwardly from the pivot point, the rear rigid arm playing through the slots in said casing and socket and adapted to normally project into the socket, a pawl pivoted to the front rigid arm and adapted to swing in a substantially vertical plane and having a raised tooth at its outer end, and an inclined top surface sloping from the tooth downwardly and rearwardly, a long flat spring associated with said pawl for yieldably holding the pawl elevated, said spring adapted to slide over said base plate, a shaft journaled in said casing, an index thereon, a disc fixed to the shaft and having downwardly extending teeth to cooperate with the tooth on the pawl, and means to hold the disc yieldably from rotation.

2. An indicator comprising a base, a casing thereon, a shaft journaled through the casing, an index on the shaft, a toothed disc on the shaft, a yieldable pawl cooperating with the teeth on the disc, a bell-crank lever pivoted at its intermediate point within the casing and having its forward arm coupled to said pawl, said bell-crank lever having a rear rigid arm, the arms diverging downwardly from the pivot point, and a substantially upright socket for a pencil adjacent said casing and receiving the rear rigid arm of the bell-crank lever, the pivot point of the lever being without the socket.

3. An indicator comprising a base plate, an inverted cup-shaped casing mounted removably on said base, a socket for a pencil supported by the base outside but adjacent the casing, said casing and socket having alining slots, a bracket secured to said base and having a shaft bearing, a shaft journaled in said bearing and projecting through said casing, an index on the shaft outside the casing, said casing having indicia co-

operating with the index, a bell-crank lever having arms forming an acute angle, said arms being both rigid and projecting downwards, the rear rigid arm playing through 5 the slots in the casing and socket, said bell-crank lever being pivoted to said bracket and at its top portion, a yieldable pawl car- ried by the forward arm, and a toothed disc on the shaft engaged rotatably on the forward movement of said pawl, and means 10 to restore the pawl, and bell-crank to initial position.

JOSIAH PERCIVAL STEVENS.
